UNITED STATES PATENT OFFICE.

MAX KÖHLER, OF LIMBACH, GERMANY.

SEAMING MACHINE.

Application filed June 18, 1925, Serial No. 37,916, and in Germany March 27, 1925.

The present invention relates to an improvement in seaming or sewing machines of a type used for uniting the edges of knitted or similar fabrics by means of a double thread or chain stitch. One object of the present invention has been to provide a seaming machine which can be operated at exceedingly high speed with a minimum of vibration. This is achieved in part by simplifying the transmission mechanism and imparting thereto the smallest possible motions to secure the necessary movement of the chain forming elements. It is also desirable in a high speed machine to dispense as far as possible with elements which result in undue frictional resistances. Where the machine is of the type in which the feeding of the work is intermittent, it will also be advantageous to provide a simple, effective and positive step by step feeding movement which will cause as little vibration as possible in the operation of the machine.

Among other objects of the present invention is that of providing a seaming machine by means of which it is possible to so control the passage of the work therethrough that the uniting chain of stitches will pass through the last courses of meshes on the fabric to be sewed together. A disadvantage in connection with some types of machines designed for a similar purpose is that the chain of stitches or loops embraces more than the outermost edge meshes of the contiguous fabrics and therefore produces an irregular and bulgy appearing seam which is highly undesirable, particularly in the manufacture of very fine stockings and other fine knit goods.

It has been found that faulty stitching or imperfect operation of the needle and looper portions of the seaming machine is frequently occasioned by variation in the direction or extent of movement of the thread with respect to the thread needle. With vibration of the machine reduced to a minimum, the chance of faulty stitching is greatly reduced but not eliminated. A further object of my invention has been to so control the tension of the thread that it will at all times assume the desired relative position with respect to the needle whereby cooperation with the looper will be more completely and accurately effected.

One embodiment of my invention is illustrated in the drawings accompanying the present specification, and in which

Figure 1 is a side elevation with portions shown in vertical section,

Figure 2, a bottom plan view with a portion of the base broken away to disclose a portion of the feeding mechanism, 60

Figure 3, a side elevation with a portion in vertical section showing the looper movement mechanism,

Figure 4, a diagrammatic representation of the movements of the looper actuating mechanism, 65

Figure 5, a rear elevation with portions broken away to illustrate in part the looper actuating mechanism and the thread needle actuating mechanism, 70

Figure 6, a horizontal section on the line 6—6 of Figure 3,

Figure 7, a horizontal section on the line 7—7 of Figure 3,

Figure 8, a detail perspective view of the 75 looper and the needle with the latter in maximum extended position,

Figure 9, a similar view with the needle in extended position and moving rearwardly,

Figure 10, a similar view with the needle 80 still moving rearwardly and with the looper in engagement with a loop of the thread carried by the needle,

Figure 11, a similar view showing the 85 needle in full retracted position and the looper in position to permit engagement of its thread by the needle on the next forward movement thereof,

Figure 12, a view in perspective illustrating the formation of the chain stitch on the 90 chaining needle.

Figure 13, a fragmentary top view of the needle and a portion of the work feeding mechanism,

Figure 14, a central vertical section showing 95 portions of the work feeding cylinders with work in operative position between them,

Figure 15, a side elevation in detail partly in section showing the needle and the thread 100 guiding mechanism with the needle in retracted position,

Figure 17, a side elevation in detail showing 105 the needle and the thread guiding mechanism when the needle is passing through the work to be united,

Figure 18, a front view of the mechanism 110 illustrated in Figure 17,

Figure 19, a side elevation in detail showing the needle and the thread guiding mechanism when the needle is in its extreme forward position, and

5 Figure 20, a front view partly in vertical section of the mechanism illustrated in Figure 19.

As indicated in the drawings, my invention may conveniently be embodied in a seaming 10 machine including a casing 1 having an interiorly disposed bracket 2 and a hollow standard or supporting member 3. A separate hollow standard or supporting member 4 is hinged to the casing at 5, Figure 3, and 15 is normally held in operative position by means of a leaf spring 6 having its free end bearing against the free end of a lever 7 secured to said standard 4. With the standard 4 movably or yieldingly mounted with respect to standard 3 as described, the fabric or 20 work to be seamed is readily inserted between a pair of feed cylinders 8 and 9 which are preferably fluted at their peripheral surfaces, as indicated in Figure 3. A main 25 shaft 10 is journaled in the casing 1 and may be rotated by any suitable means, such for example as an electric motor, not shown, from which power may be transmitted by a belt to a pulley 11 mounted on shaft 10.

30 As shown in Figure 1, the cylinders 8 and 9 are attached to spindles 12 and 13, respectively, which are mounted in and extend through the standards 3 and 4. A grooved clutch pulley 14 is secured to the spindle 12 35 and cooperates with a plurality of wedge pawls 15 pivotally mounted on an oscillatable disc 16 at 23, said disc being pivotally mounted on the spindle 12 and actuated from the shaft 10 through an eccentric 17, a lever 18 40 pivoted at 19, and a link 20 connected to the disc 16 by a ball and socket joint including a crank pin having a ball 21 cooperating with a socket on the link 20. The wedge pawls 15 are retained normally in engagement with 45 the groove of the pulley 14 by means of springs 22. Thus, when the link 20 is moved in the direction of the arrow, Figure 2, the disc 16 will be rotated in a clockwise direction and the pawls 15 will be deflected in such 50 a way as to ride across the clutch pulley 14 without turning it. This operation is insured by means of a brake pawl 24 pivoted at 55 on a bracket 26 and having its free end held in operative engagement with the clutch pulley 14 by means of a spring 27. Upon the return stroke of the link 20, the brake pawl 24 becomes inoperative and the pawls 15 then engage the clutch pulley 14 to rotate the same and thereby the spindle 12. A gear 28, Figure 1, is mounted on the spindle 12 and meshes 60 with a gear 29 on the spindle 13, thus driving the feed cylinder 9. It will be understood that the step by step movement produced by the mechanism hereinabove described or by 65 other suitable variation thereof, is intended

to advance the feed cylinders by an amount substantially equivalent to the distance between the centers of adjacent fabric meshes so that in operation, the needle and the looper will cooperate with the fabric in such a way 70 as to form a chain loop for each pair of united fabric loops. The length of each feeding movement depends upon the extent of rotation of the disc 16 and can be varied by adjusting the position of the link 20 with respect to a slot 30 in the lever 18, the longest stroke being effected when the connection between the said lever and the link 20 is at the extreme outer end of the slot 30.

As shown in Figure 1, a thread needle 31 80 is mounted in a head 32 carried on a rod 33 slidably mounted in bearings 34 and 35 formed in the bracket 2. Reciprocatory movement is imparted to said rod 33 by means of a lever 36 pivoted at 37 and a link 38. A 85 connecting rod 39 has one end secured to the lever 36 at 40, the other end being in engagement with an eccentric 41, Figure 7, mounted on the main drive shaft 10.

As indicated in Figure 3, the hook or looper 90 42 is mounted at one end of a rod 43, said rod being supported by a carrier or bushing 44 and free to rotate therein. Forward and backward movement of the carrier 44 is effected by means of a bell crank 45 pivoted at 95 46 and actuated by means of a connecting rod 47 which is in turn operated by an eccentric 48 mounted on the main drive shaft 10.

Vertical oscillatory movement of the looper carrier 44 is secured by means of a lever 49 pivoted at 50 and connected to said carrier by means of a link 51. Rocking movement of the lever 49 is produced by means of an eccentric 52 mounted on main drive shaft 10 and a connecting rod 53 interposed between said lever 49 and the eccentric 52. The operation of the looper carrier 44 and the course of movement of the end of the looper mounted thereon will be better understood by reference to Figure 4 of the drawing. Thus when the looper is in retracted position as at A, or as illustrated in Figures 15 and 16, the vertical and horizontal reciprocating mechanisms occupy the respective positions indicated by the full lines in said diagram. When the looper occupies the other or outer extreme position as at B, or as illustrated in Figures 19 and 20, the vertical and horizontal reciprocating mechanisms occupy the relative positions indicated by the broken lines in the diagram. Similarly, the mean or intermediate position C, as illustrated in Figures 17 and 18, is attained when the parts occupy the relative positions indicated by the dotted lines in the diagram.

As shown in Figure 3, the link 51 is preferably formed in two parts with an intermediate portion 54 which is threaded or provided with other suitable means whereby the effective length of link 51 can be increased or

diminished thereby increasing or diminishing the vertical displacement of the carrier 44. While the carrier 44 is being subjected to simultaneous vertical and horizontal reciprocating movements, the rod 43, rotatably mounted in said carrier, is periodically rotated to produce a transverse arcuate movement of the thread carrying end of the looper 42. This rotation is effected by a short lever 55, Figure 5, secured to the rod 43 and connected by means of a ball and socket joint 56 with a connecting rod 57 engaging an eccentric 58 mounted on main shaft 10. The rod 57 consists of separate parts joined by an intermediate piece 59 which is threaded or provided with other suitable means whereby the effective length of the rod can be varied to synchronize or adjust the rotative movement of rod 43 with respect to the vertical and horizontal or endwise movements thereof.

From the foregoing description of the needle and looper actuating mechanisms, it will be apparent that a seaming machine embodying my invention will be capable of high speed operation, that there will be relatively little vibration on account of the short throw of moving parts and the fact that practically all moving parts are balanced. Furthermore, the construction illustrated is capable of minute regulation and adjustment so that the parts can be made to articulate with the highest degree of accuracy.

Referring to Figures 1, 13, 14 and 16, it will be noted that my improved machine is equipped with a pair of cooperating yielding fabric or work guides 60 and 61 and an intermediate guide 62, all supported in operative position on a bracket 63 by means of depending arm 64 pivotally secured thereto at 65 and movable toward and from the feed cylinders 8 and 9. The bracket 63 is adjustable vertically thereby permitting movement of the guides 60, 61 and 62 in a vertical direction to adjust the position of the upper edge of the work so that the needle 31 may engage and unite the outermost loops or meshes of the fabric. A screw having a thumb piece 66 engages the bracket 63 to hold it in operative position. The manner of assembly of the work in the machine is more clearly shown in Figures 13 and 14 wherein 67 and 68 represent the work of which the edges are to be united. A bracket 69 supported by the casing 1 and extending across the cylinder 8 carries a chaining finger 70 lying just above the path of the needle 31, Figure 14, and affording a guide for the upper edges of the fabrics to be joined. The other function of the chaining finger will be better understood by reference to Figures 8 to 11 inclusive which show that the combined operations of the looper 42 and the needle 31 produce thereon a continuous chain of stitches formed by the interlocking of the looper thread 72 and the needle thread 71, said chain being carried off and

beyond the chaining finger as the work is fed beyond the cylinders 8 and 9.

As indicated more clearly in Figures 6, 7 and 20, the needle 31 is positioned to reciprocate between the inner or discharge ends of 70 the work guides 60, 61 and 62 and a plane defined by the central vertical axes of the feed cylinders 8 and 9. Heretofore in sewing machines of similar type the needle has been positioned to reciprocate in the plane defined 75 by the central vertical axes of the feed cylinders, or substantially above the line of contact between said cylinders. In my improved device the loop or stitch forming operation of the needle is effected at a point nearer to 80 the inner ends of the work guides at which position there is less likelihood that the edge meshes of the fabrics to be joined will have curled out of position to effectively receive the advancing needle. Curling of the fabric 85 edge after it leaves the guides presents the meshes in such a manner that the needle engages meshes other than those at the edge, thus resulting in a bunching or thickening on the seam.

In order to form a continuous and therefore effective chain of interlocking loops, it is essential not only that the accurate cooperation of the looper and the needle be established, but also that the threads carried by 95 these parts respectively shall constantly assume certain predetermined relative positions with respect to said looper and needle. The problem is not so difficult with respect to the thread 72 or that carried by the looper, 100 inasmuch as it is under some tension at the time the needle moves forward to engage it, Figure 11. However, there is frequently difficulty with the operation of thread 71 carried by the needle. As shown in Figure 9, 105 looper 42 is about to engage an upstanding loop of the thread 71. Obviously, if the machine is vibrating excessively or if the tension on thread 71 is not accurately adjusted, it is not unusual for the loop to be displaced 110 or deformed in such a manner that the looper 42 will fail to engage it as intended. This difficulty I control in part by providing 115 improved tensioning mechanism for the thread 71.

As shown in Figure 15, the threads 71 and 72 are brought down over a thread brake 73 and pass through the openings in fixed thread guides 74 and 75 respectively. The thread 72 passes through an opening in a movable guide 76 and thence to the looper 42. The head 32 which carries needle 31 is provided with a movable guide 77 through which the thread 71 passes on its way to the needle 31. Between the fixed guide 75 and the movable guide 77 is a pin or rod 78 secured at one end to the casing 1 and provided at the opposite or free end with a hook 79. The thread 71 engages the surface of said rod which lies adjacent to the hook 79, said surface being 125 130

of cam shape or of irregular contour as indicated more clearly in Figures 6 and 7. A flat spring 80 is positioned to yieldingly engage a portion of said cam surface of the rod 78 and extends from the base thereof to a point between the hook 79 and the thread engaging face of the rod 78. In operation, when the needle 31 moves forward and back, the thread is constantly guided adjacent to 10 the guide 77 and its passage between the rod and said spring is subject to varying frictional resistance, increasing in the rearward direction and diminishing in the forward direction. Furthermore, only very small increments of thread are exposed between 15 guides so that there is little or no harmful effect of the weight of the thread on the formation of the upstanding loop hereinabove referred to. The improved tensioning mechanism also makes it impossible for an excess of thread to be presented at the end of the needle. This prevents the loop from becoming unduly large and avoids the occurrence of vibration or flutter which is detrimental 20 to accurate operation. In the retracted position or dead motion point of the needle, the thread is loose at the forward end and is held under increased resistance to passage by the spring 80. However, as the needle approaches 25 its most advanced position, the resistance is not so great and the thread therefore runs more easily.

The improved construction hereinabove described makes it possible to embody all of 30 the power transmission parts of my improved machine within the casing, thus producing a very compact appearance and making it possible to protect the moving parts from dust and accidental injury.

40 I claim as my invention:

1. A seaming machine comprising work supporting and feeding means consisting of a pair of cooperating peripherally contiguous cylinders, work guiding means having 45 portions positioned between said cylinders to present work for engagement by said cyl-

inders, a thread needle, and needle actuating means positioned and adapted to reciprocate said needle through the work at one side of a plane passing through the axes of said cylinders.

2. A seaming machine comprising a pair of peripherally contiguous cylindrical work supporting and feeding members, work guiding means having portions positioned between said cylinders to present work for engagement between said members, and a thread needle positioned to reciprocate across the path of travel of the work and between said guiding means and the line of contiguity between said cylinders.

3. A seaming machine comprising a casing, a looper supporting carrier therein, a drive shaft, a lever having one end operatively connected with said shaft, a link having one end pivoted to said carrier and the other end operatively connected to said lever, a bell crank fulcrumed above the path of said carrier and having a bifurcated depending arm, opposed pivotal carrier supporting connections between said arm and said carrier, and means operatively connecting the drive shaft with the other arm of said bell crank.

4. A seaming machine comprising a casing, a partition extending rearwardly from the front wall of said casing and forming a bracket having spaced bearings, a reciprocating needle carrier slidably mounted in said bearings, means positioned at one side of said bracket for engaging and operating said carrier, a looper carrier pendularly supported in the casing above said needle carrier, means positioned at the other side of said bracket for engaging and operating said looper carrier, and a main drive shaft effectively connected with said needle carrier and looper carrier operating means.

In testimony whereof, I have signed my name to this specification this first day of May, 1925.

MAX KÖHLER.
